Specification of Letters Patent. Patented Aug. 29, 1922.

Application filed August 22, 1919. Serial No. 319,084.

To all whom it may concern:

Be it known that we, EDWARD J. MOORE and RAYMOND H. MOORE, citizens of the United States, residing at Cleveland, in the 5 county of Cuyahoga and State of Ohio, have invented a certain new and useful Improvement in Separators, of which the following is a full, clear, and exact description, reference being had to the accompanying 10 drawings.

This invention relates to separating apparatus, and more particularly to apparatus designed to separate various grades of sand or cleaning material from the dust mingled therewith. The general object of the invention is to improve and increase the efficiency of such apparatus. Further and more limited objects of the invention will appear hereinafter and will be realized in 15 and through the combinations of elements embodied in the claims hereto annexed and illustrated in the drawings forming a part hereof, wherein Fig. 1 represents a sectional view of such apparatus, corresponding substantially with the line 1—1 of Fig. 2, certain parts being broken away; Fig. 2 a sectional view corresponding to the line 2—2 of Fig. 1; Fig. 3 a detail in perspective of the valve mechanism connected with one of the 20 delivery outlets from the apparatus; and Fig. 4 a sectional view corresponding to the line 4—4 of Fig. 1 and looking in the direction of the arrows.

Describing the various parts of the drawing by reference characters, 1 denotes a pipe, the inlet end whereof may communicate with the bottom of a screened hopper and with the dust space therein, such as shown in our copending application No. 319,083, 25 filed August 22, 1919. The upper or delivery end of this pipe extends through the inclined bottom 2 of a separating casing, indicated generally at 3, said casing having an outlet connection 4 at the top thereof leading to the dust collector (not shown). The inclined bottom 2 may be formed on a bottom section suitably secured within the bottom of the casing 3 and having a vertical wall 5 with which the lower end of the inclined wall 2 is connected. Immediately 30 above the lower end of the inclined wall 2, the wall 5 is provided with a wide slot or opening 6 leading to a downwardly extending chute 7 secured over said slot or opening and provided with baffles 8 projecting

from one wall thereof and a baffle 9 projecting from the opposite wall between and overlapped by the ends of the former baffles. The upper end of the pipe 1 is shown as extending somewhat above the top 60 of the bottom section and communicating with a chamber within the casing formed by a vertical wall 10 connecting the side walls 11 of said casing and an upwardly inclined wall 12 also connecting the said side walls 65 and extending from the top of the wall 10. The upper end of the wall 12 is preferably curved to provide a bearing against the wall 13 of the casing. This wall is provided, below the top of the wall 12, with an opening 70 which may be closed by a sliding door 14.

15 denotes a wall or partition secured at its lower end to the wall 16 of the casing and extending upwardly therefrom, being secured to the walls 11, as by angle clips 17. 75 This wall forms with the wall 12 and the walls 11 of the casing a duct which is gradually enlarged from the bottom to the top thereof. Extending above the upper ends of the walls 12 and 15 and projecting inwardly from the wall 13 is a horizontal baffle 18. This baffle may be secured to the walls 11 as by means of angle clips 19.

Immediately above the junction of the bottom of the wall 15 with the wall 16 the 85 latter is provided with a slot or opening 20 communicating with a hopper 21 having a discharge chute 22. Extending around three sides of this chute is a guard 24, which may be supported from the said chute. Secured 90 to said chute are arms 25 in the projecting ends of which there is mounted a rod 26. Mounted on the ends of this rod is a U-shaped bracket 27 supporting a swinging valve 28. The valve is connected intermediate of its ends to the bracket, the outer end being provided with a counterweight 29 which tends to hold the valve against the bottom of the chute.

The apparatus hereinbefore described is 100 designed for the purpose of recovering from the screened hoppers of said blast apparatus various grades of sand delivered through the screens and separating the dust therefrom. In operation, air laden with sand and 105 dust will be forced into the casing 3 through the pipe 1 and into the open-bottomed chamber provided beneath the wall 12. The shape of this wall and the arrangement of the chamber outlet between the bottom of 110

the wall or partition 10 and the reversely inclined bottom 2 imparts a whirling motion to the air and its contents, and the heavier and coarser particles of sand that can be reused for said-blasting purposes will be thrown down and discharged into the baffled chute 7, the baffles therein preventing any material interference with the whirling action through the entry of air into the chamber with which 5 it communicates. From this preliminary separating chamber, the air laden with finer and lighter sand and dust passes upwardly between the plates 12 and 15 toward the wall 13 and is directed and whirled laterally toward the wall 16 by the baffle 18. The lighter sand, which is suitable for the making of cores, will be separated from the air by this last whirling movement and discharged into the hopper 21 by the walls 10 15 and 16 through the slot 20. When a sufficient quantity of this sand has accumulated upon the valve 28, the latter is automatically opened and the sand discharged from the bottom of the hopper, the guard 24 20 serving to prevent lateral dispersion of this sand and to guide it to a suitable receptacle. From the upper part of the casing 3 the air, now laden with dust, may be conducted to a suitable dust arrester or collector (not 25 shown).

Having thus described our invention, what we claim is:—

1. A separator of the character described comprising a casing having an inclined bottom, with an opening above said bottom, an inlet pipe extending through and above said bottom, an upwardly inclined wall forming with the casing above the said opening and with the inclined bottom an open-bottomed chamber extending above the delivery end of said pipe, an upwardly inclined plate connected at its bottom to the wall of the casing opposite the said opening and forming with the inclined top of said chamber a passageway, the second wall of said casing being provided with an outlet above the lower end of the second inclined wall, a baffle extending from the first mentioned casing wall across the space provided between the tops of the inclined walls within the casing, an outlet connection from the casing above said baffle, and a chute extending downwardly from the second opening.
2. A separator of the character described comprising a casing having an inclined bottom with an opening above said bottom, an inlet pipe extending through and above said bottom, an upwardly inclined wall forming with the casing above the said opening and with the inclined bottom an open-bottomed chamber extending above the delivery end of said pipe, an upwardly inclined plate connected at its bottom to the wall of the casing opposite the said opening and forming with the inclined top of said chamber a passageway, the second wall of said casing being provided with an outlet above the lower end of the second inclined wall, a baffle extending from the first mentioned casing wall across the space provided between the tops of the inclined walls within the casing, an outlet connection from the casing above said baffle, and a valve for the outlet of said chute.
6. In a separator of the character described, the combination of a casing having an inclined bottom and a discharge opening above the lower end of such bottom, a pipe communicating with said casing above said bottom, means forming about the delivery end of said pipe and with said bottom an open-bottomed chamber above said outlet, means forming within said casing a second chamber communicating at its bottom with the first chamber and extending upwardly therefrom having a discharge outlet, and an outlet from said casing above the second chamber.
7. In a separator of the character described, the combination of a casing having an open-bottomed chamber in the lower portion thereof and an inlet pipe communicating with said chamber, means within said

the inclined top of said chamber a passageway, the second wall of said casing being provided with an outlet above the lower end of the second inclined wall, a baffle extending from the first mentioned casing wall above the space provided between the tops of the inclined walls within the casing, and an outlet connection from the casing above said baffle.

3. A separator of the character described comprising a casing having an inclined bottom with an opening above said bottom, an inlet pipe extending through and above said bottom, an upwardly inclined wall forming with the casing above the said outlet and with the inclined bottom an open-bottomed chamber above the delivery end of said pipe, an upwardly inclined wall forming with the inclined top of said chamber a passageway, communicating at its bottom with said chamber, the said casing being provided with an outlet above the lower end of the second inclined wall, a baffle extending from the casing into said passageway and an outlet connection from the casing above said baffle.

4. A separator of the character described comprising a casing having an inclined bottom with an opening above said bottom, a delivery chute enclosing said opening and extending downwardly therefrom, an upwardly inclined wall forming with the side of the casing above the said outlet and with the inclined bottom an open-bottomed chamber, an inlet pipe communicating with said chamber, an upwardly inclined plate connected at its bottom to the wall of the casing opposite the said opening and forming with the inclined top of said chamber a passageway, the second wall of said casing being provided with an outlet above the lower end of the second inclined wall, a baffle extending from the first mentioned casing wall across the space provided between the tops of the inclined walls within the casing, an outlet connection from the casing above said baffle, and a chute extending downwardly from the second opening.

5. In a separator, the combination of a casing having an inclined bottom and a discharge opening above the lower end of such bottom, a pipe communicating with said casing above said bottom, means forming about the delivery end of said pipe and with said bottom an open-bottomed chamber above said outlet, means forming within said casing a second chamber communicating at its bottom with the first chamber and extending upwardly therefrom having a discharge outlet, and an outlet from said casing above the second chamber.

6. In a separator of the character described, the combination of a casing having an open-bottomed chamber in the lower portion thereof and an inlet pipe communicating with said chamber, means within said

- casing forming a second chamber above and communicating at its bottom with the first chamber, whereby the fluid supplied to the first chamber through said pipe is caused 5 to whirl, there being an outlet in said casing at the bottom of the first chamber for the particles separated by such whirling motion, and means within said casing and located beyond the first chamber for 10 separating lighter material from the fluid supplied to the casing, the said casing having an outlet for such lighter material.
7. In a separator of the character described, the combination of a vertical casing having an outlet in the upper portion thereof and having an inclined bottom and an outlet thereabove, a fluid supply pipe delivering above the bottom of the casing, a wall within said casing forming therewith 15 and with the bottom a preliminary open-bottomed separating chamber communicating with the second outlet, said chamber also having an outlet beneath said wall, and a baffle interposed between the third outlet 20 and the first outlet.
8. In a separator, the combination of a casing having an outlet in the upper portion thereof, a bottom, and an outlet above said bottom, a fluid supply pipe communicating 25 with said casing above the bottom thereof, means within said casing forming a chamber communicating with the second outlet and wherein the fluid is subjected to a whirling action, a second chamber in said casing communicating with the first chamber and interposed between the same and the first outlet and wherein the fluid leaving the first chamber is subjected to a further whirling action, and an outlet from the bottom of the second chamber. 30
9. In a separator, the combination of a casing having an inclined bottom and an outlet at the lower end of said bottom, a fluid supply pipe extending through and 35 above said bottom, a wall within the casing 40
- extending from the top of said pipe and forming with the casing a separating chamber wherein the fluid supplied to said pipe is whirled, a second chamber in said casing communicating with the first mentioned 50 chamber below said wall and wherein a second whirling motion is imparted to the fluid, and an outlet from said second chamber.
10. A separator comprising a casing having an outlet, a fluid supply pipe communicating with said casing, means within said casing for separating particles from the fluid supplied by said pipe, and an outlet from said casing for the particles so separated the said outlet having a downwardly extending chute, a U-shaped guard secured in operative relation to the delivery end of said chute and projecting downwardly therefrom, and a valve plate pivoted intermediate of its ends from said guard and adapted normally to close the lower end of said chute, the downwardly opening edge of said valve being adjacent the middle branch of said guard. 55
11. A separator comprising a casing having an outlet, a fluid supply pipe communicating with said casing, means within said casing for separating particles from the fluid supplied by said pipe, and an outlet from said casing for the particles so separated, the said outlet having a downwardly extending chute, a guard secured in operative relation to the delivery end of said chute and projecting downwardly therefrom, and a valve plate pivoted intermediate of its ends to said guard and adapted normally to close the lower end of said chute, the downwardly opening edge of said valve being within said guard. 60 65 70 75 80 85

In testimony whereof, we hereunto affix our signatures.
